UNITED STATES PATENT OFFICE

FRANCIS J. RICHARDSON, OF NEW ORLEANS, LOUISIANA

FOLDING METALLIC AWNING

Application filed September 27, 1930. Serial No. 484,871.

This invention relates to a metallic awning, the general object of the invention being to so form and arrange the parts that air and light rays can readily pass through the awning, the light rays being diffused so that no direct rays will enter the window or other opening over which the awning is placed, and the awning also acts as a screen for preventing one from looking into the window through the awning.

A further object of the invention is to so construct and arrange the parts that the awning can be rolled in either direction upon a roller or folded into a compact bundle and as all the parts of the awning are formed of metal, the awning is fireproof.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is a front view of the awning.

Figure 2 is a sectional view showing the awning in operative position in front of a window.

Figure 3 is a sectional view showing the awning partly rolled upon a roller.

Figure 4 is a section on line 4—4 of Figure 1.

Figure 5 is a detail view of a modification.

As shown in these views, the awning A is composed of the metallic strips 1 and 2 which are held together by the metallic flexible members 3, such members being looped around the strips, as shown, with the upper portions of the flexible members connected to brackets 4 which are fastened to a roller 5 rotatably supported by the brackets 6 at the top part of a window or other opening B. The strips 1 are of greater width than the strips 2 and the strips 1 alternate with the strips 2 so that the awning can be readily rolled on the roller 5 without mak-

ing the roll unduly large, as would be the case if all the strips were of the same size. The strips 1 and 2 may be of channel form, as shown in Figures 1 to 4, or they may be of rectangular form, as shown at 1' and 2' in Figure 5. It is essential, however, that the strips be of considerable thickness so that their sides will be of sufficient width to cause diffusion of the light rays passing through the spaces between the strips, as well as to prevent direct vision through the spaces between the strips into the window. The flexible members hold the strips in spaced relation so that light and air can pass through the spaces between the strips, though the light rays are diffused, as before explained. The lower strip has a lower depending part 7 which may be corrugated at its lower edge to give the lower part of the awning a finished appearance. The lower part of the awning is connected with the usual member 8 which is pivoted to the lower part of the window frame, as shown at 9, so that said member can be swung upwardly or downwardly as the awning is being rolled or unrolled from the roller 5. The roller 5 can be actuated in any desired manner, such as by a spring or a handle.

As many of the flexible members can be used as is necessary to properly support the strips and in order to prevent longitudinal movement of the strips, metallic flexible members 10 are passed through holes 11 in the strips. I prefer to place one of these flexible members 10 adjacent each side edge of the awning.

From the foregoing it will be seen that the awning can be rolled in either direction on the roller 5 and due to the alternate arrangement of the large and small strips, the awning will be rolled compactly on the roller. As before stated, air and light can readily pass through the awning, though the light rays are diffused and no direct rays enter the window and as all the parts of the awning are of metal, the awning is fireproof.

It is thought from the foregoing descrip-

tion that the advantages and novel features of the invention will be readily apparent.

It is to be understood that changes may be made in the construction and in the combination and arrangement of the several parts, provided that such changes fall within the scope of the appended claim.

What I claim is:—

In an awning construction of the class described, a series of grouped metal strips of considerable thickness and of substantially U-shape in cross section, flexible members reversely looped around alternate strips from the outside of one strip to the inside of the next strip adjacent thereto for holding them together in spaced relation, flexible members loosely passing through the strips for preventing longitudinal movement of the strips, a supporting roller having the upper ends of the first mentioned flexible member connected thereto and a pivoted member having its outer part connected with the lower part of the grouped strips, said first and second named flexible members being arranged in spaced relation to each other longitudinally of said grouped strips.

In testimony whereof I affix my signature.
FRANCIS J. RICHARDSON.
